STRAIGHT-BAR KNITTING MACHINE

Harry Wilfred Start, Carlton, and Ernest Start,
Wilford, England, assignors to George Black-
burn and Sons Limited, Nottingham, England

Application March 3, 1944, Serial No. 524,918
In Great Britain January 14, 1943

8 Claims. (Cl. 66—82)

This invention relates to improvements in straight-bar knitting machines and refers to an improved mechanism for driving the reciprocating parts of such machines.

In straight-bar knitting machines as hitherto constructed the slur bar and the main friction bar which drives the thread carrier bars are driven by the Coulier mechanism which comprises a cam adapted to reciprocate a slide which is in turn connected to a pivoted lever the free end of which is connected to the slur bar and main friction bar. The cam is driven from the main shaft of the machine and the slide is connected to the lever intermediate its ends so that the free end of the lever provides a motion approximately three times that of the slide. The Coulier mechanism is of substantial construction in order to transmit the necessary power to drive the reciprocating parts and is consequently of appreciable weight. As is well known the Coulier mechanism is disconnected from the main shaft of the machine when narrowing and also when certain other operations are being carried out. Owing to the speed at which modern straight-bar knitting machines run a brake has to be provided to stop the Coulier mechanism in the correct position when it is disconnected from the main shaft and this causes considerable wear and tear on the mechanism. Furthermore in the Coulier mechanism the pivoted lever stands at the end of each draw and has to be restarted at the commencement of each draw. The time taken for the lever to move from rest up to its maximum speed and consequently the time taken to move the reciprocating parts from rest up to their maximum speed is a part of the time taken to complete a knitting cycle so that any decrease in the time taken to move the reciprocating parts from rest up to their maximum speed produces a corresponding decrease in the time taken to complete a knitting cycle. Owing to the particular construction of the Coulier mechanism any defects in the driving cam are accentuated by the free end of the lever and consequently when wear develops in the mechanism the lever tends to 'chatter' and transmits an unsteady drive to the reciprocating parts.

The object of the present invention is to provide a drive for the reciprocating parts of the machine which is lighter in weight than that used hitherto and consequently requires less effort to start and stop, which takes less time to move the reciprocating parts from rest up to their maximum speed and will transmit a steady drive.

According to this invention the driving mecha-

nism for the reciprocating parts of a straight-bar knitting machine comprises a slide connected to the reciprocating parts, a member continuously driven from the main shaft of the machine during knitting and a driver on the continuously driven member connected to the slide to reciprocate the latter.

The invention will now be more particularly described with reference to the accompanying drawings in which:

Fig. 1 is a rear view.

Fig. 2 a plan and

Fig. 3 an end view of driving mechanism for the reciprocating parts of a straight-bar knitting machine constructed according to this invention.

Fig. 4 is a view of part of the mechanism illustrating the path traversed by the driver.

Like letters indicate like parts throughout the drawings.

Only sufficient of the mechanism of a straight-bar knitting machine to enable the invention to be understood is shown in the drawings.

In the preferred construction the continuously driven member consists of two endless chains A, A¹ mounted on a series of sprockets and carrying a driver B connected to the slide C to move the latter first in one direction and then in the other direction. One or more of the sprockets are driven from the main shaft D of the machine by suitable gearing incorporating a clutch which is disengaged when the main shaft is shogged longitudinally in well known manner to bring the narrowing mechanism into operation and for other purposes.

The endless chains A, A¹, are each mounted on four sprockets 1, 2, 3, 4, which are disposed one at each corner of a rectangle so as to provide two chains in parallel planes. Each sprocket is mounted on an axle disposed in bearings in the sides of the fixed framing E and are arranged so as to provide four pairs of co-axial sprockets. A driver B is disposed between the chains A, A¹, and is carried by two pins C¹, C² (see Fig. 4), the outer ends of which form adjacent link connecting pins in the respective chains so that the driver moves with the chains. The chains are driven from the main shaft D of the machine and for this purpose one or more of the sprockets in each set are driven. In the arrangement shown in the drawings the upper sprockets 1 and 2 of each set are driven by the following arrangement. Disposed on the main shaft D is a bevel wheel F driven from the main shaft by a dog clutch G and engaging a bevel wheel H secured to one end

of a shaft to the other end of which is secured a gear wheel J. This gear wheel J engages with gear wheels K, L secured on the axles of the sprockets 1 and 2 associated with the chain A. The sprockets 1 and 2 associated with the chain A¹ are driven by the gear wheel M engaging gear wheels N, O secured on the axles of the respective sprocket wheels, the gear wheel M being driven from the gear wheel J by a pair of gear wheels P, Q, mounted on a cross shaft R. It will therefore be seen that when the dog clutch G engages with the bevel wheel F and the main shaft is rotated the chains A, A¹ will move together and the driver B be carried round therewith. The ratio of the gearing between the main shaft and the sprockets is so arranged that the driver B makes one complete circuit round the sprockets that is from its starting point round again to its starting point every two revolutions of the main shaft.

Referring to Fig. 4 it will be seen that by disposing the sprockets 1, 2, 3 and 4, as described two pairs of oppositely running lengths of chain are provided. The driver B is connected to the slide C so that the latter moves from left to right as the driver travels from a to b, is stationary or practically stationary whilst the driver moves from b to c, moves from right to left as the driver moves from c to d and is stationary or practically stationary whilst the driver moves from d to a. The mechanism is arranged so that the driver moves from a to c during one revolution of the main shaft D of the machine and from c to a during the next revolution of the main shaft. As the driver B moves from a to b the slide actuates the reciprocating parts of the machine to draw a course in well known manner from left to right. As the driver moves from b to c the course thus drawn is knitted. A course is then drawn from right to left as the driver moves from c to d and the course thus drawn knitted as the driver moves from d to a.

It will also be seen that as the driver B moves from a to e the slide C and consequently the reciprocating parts will be moved from rest up to their maximum speed by an increasing acceleration, will move at a constant speed as the driver moves from e to f and be brought from their maximum speed to rest as the driver moves from f to b. Similarly the reciprocating parts will be moved from rest up to their maximum speed as the driver moves from c to g and from maximum speed to rest as the driver moves from h to d.

The connection between the driver B and the slide C may comprise a second slide having a fork thereon which embraces the driver and is so disposed that the driver B travels along the fork as it moves between the points b and c and d and a of its motion so that the slide and consequently the reciprocating parts are stationary at these times. Alternatively the driver B may be connected to the slide C by a link B¹ as shown in the drawings. This arrangement provides a simple form of construction and provided the link B¹ is sufficiently long any motion of the slide C as the driver moves between the points b and c and d and a is so slight as to be negligible especially if the thread carriers are arranged so as to be positively driven.

The slide C is connected to the slur bar S (see Fig. 3) so as to reciprocate it and the slur cocks carried thereby and may also be connected to a carrier driving bar or other suitable carrier driving mechanism. If preferred a separate chain

drive and associated slide may be provided to drive some or all of the thread carriers.

The arrangement described is put out of action, as is necessary, when the main shaft of the machine is shogged to bring the fashioning cams into action or cams for operating automatic welt turning mechanism. The shogging of the main shaft D disengages the dog clutch G and disconnects the bevel gear F from the main shaft. In order to stop the chain driving mechanism when the clutch G is disengaged a brake is provided. This brake comprises a brake shoe T which is moved into engagement with a brake drum U on the bevel wheel H at the appropriate time by an angularly adjustable arm V connected to the brake shoe by a link W. The arm V is angularly adjusted to apply the brake when the clutch G is disengaged by a flange G¹ on the clutch engaging a roller V¹ on the arm V.

Provision may be made for taking up any slack in the chain which may arise from wear and for this purpose the axles of the sprocket wheels 3 and 4 associated with each chain may be located in eccentric bushes E¹ carried in housings in the fixed framing E.

The bushes E¹ are rotated in their housings to take up any slack in the chains and any convenient method of securing them in the desired position may be adopted.

The sprockets which carry the chains are spaced apart a sufficient distance to provide the necessary stroke to the reciprocating parts and the necessary dwell at the end of each reciprocating motion to permit of the knitting of the course drawn thereby. In order to prevent any whip in the chains when the driver is transmitting motion to the slide, guide plates may be provided on both sides of the chains. The guide plates are secured to the fixed frame E and only sufficient space is provided between them to allow the chains to pass so that lateral movement of the latter is prevented.

The mechanism described is running continuously during knitting. It is light in weight so that less effort is required to stop it and re-start it when necessary with a consequent reduction in wear and tear and by the use of small sprockets the time taken to bring the slide up to its maximum velocity and to bring it to rest at the end of its traverse is reduced to a minimum and a steady drive for the slide and consequently the parts driven thereby is obtained.

What we claim as our invention is:

1. Mechanism for driving the reciprocating parts of straight-bar knitting machines comprising two endless chains disposed in parallel planes, a driver disposed between the chains and carried thereby, sprockets to support the chains, means to drive the chains and means to connect the driver to the reciprocating parts.

2. Mechanism for driving the reciprocating parts of straight-bar knitting machines comprising two endless chains disposed in parallel planes and each mounted on four sprockets, a driver disposed between the chains and carried thereby, means to drive one or more of the sprockets associated with each chain and means to connect the driver to the reciprocating parts.

3. Mechanism for driving the reciprocating parts of straight-bar knitting machines comprising two endless chains each mounted on four sprockets a driver disposed between the chains and carried thereby, a driving connection between one or more of the sprockets associated with each chain and the main shaft of the ma-

chine and means to connect the driver to the reciprocating parts.

4. Mechanism for driving the reciprocating parts of straight-bar knitting machines comprising two endless chains each mounted on four sprockets, a driver disposed between the chains and carried thereby, a driving connection between one or more of the sprockets associated with each chain and the main shaft of the machine, a clutch in the driving connection which is disengaged when the main shaft is moved longitudinally and means to connect the driver to the reciprocating parts.

5. Mechanism for driving the reciprocating parts of straight-bar knitting machines comprising two endless chains each mounted on four sprockets, a driver disposed between the chains and carried thereby, a driving connection between one or more of the sprockets associated with each chain and the main shaft of the machine, a clutch in the driving connection, a brake to stop the chains when the clutch is disengaged and means to connect the driver to the reciprocating parts.

6. Mechanism for driving the reciprocating parts of straight-bar knitting machines comprising two endless chains each mounted on sprockets, a driver disposed between the chains and

carried thereby, a driving connection between one or more of the sprockets associated with each chain and the main shaft of the machine, a slide connected to the reciprocating parts and a link connecting the driver to the slide.

7. Mechanism for driving the reciprocating parts of straight-bar knitting machines comprising two endless chains each mounted on sprockets, a driver disposed between the chains and carried thereby, a driving connection between one or more of the sprockets associated with each chain and the main shaft of the machine, means to adjust the tension in the chains, and means to connect the driver to the reciprocating parts.

8. Mechanism for driving the reciprocating parts of straight-bar knitting machines comprising two endless chains each mounted on four sprockets, a driver disposed between the chains and carried thereby, a driving connection between two of the sprockets associated with each chain and the main shaft of the machine, axles on the remaining sprockets disposed eccentrically in rotatable bushes, and means to connect the driver to the reciprocating parts.
